LOCK AND LATCH

Gaylord A. Brinson, Moreland, Ind.

Application October 19, 1945, Serial No. 623,226

2 Claims. (Cl. 292—172)

1

My invention relates to improvements in locks and latches and the primary object of my invention is to provide a latch having its operating handles located within the general outer contour of the latch casing or housing for the operating means.

It is an object of my invention to provide a lock casing or housing with external recesses to receive the manipulating handles, knobs or bars.

It is an object of this invention to provide an operating mechanism for the latch bolt comprising racks and a pinion in which the racks and pinion are actuated in one direction by a spring and in the opposite direction by manual means.

It is an object of my invention to provide recessed finishing plates adapted to be secured to the lock or latch and to the closure to which the latch is applied.

It is also an object of my invention to provide a movable locking or blocking element that may be moved into the path of, at least, one rack bar or member to prevent operation of the latch bolt.

It is also an object of my invention to provide movable finger contact pieces or bars located in the recesses of the finishing plates and preferably guided by slide ways provided for the same.

Other objects and advantages will be revealed in connection with the detailed description of the drawings forming a part of the specification.

In the drawings:

Figure 1 is perspective schematic view of the operating parts of my new latch construction.

Figure 2 is a side elevation of my latch when applied to a hinged closure.

Figure 3 is a transverse vertical section taken on the line 3—3 of Figure 2 looking in the direction indicated by the arrows.

Figure 4 is a vertical longitudinal section taken on the line 4—4 of Figure 3 looking in the direction of the arrows.

Figure 5 is a vertical transverse section of a fragment of the operating means for my latch.

Figure 6 is a sectional view of a fragment of my lock showing the movable locking element.

Figure 7 is a section of my locking means taken substantially on the line 7—7 of Figure 6 looking in the direction of the arrows.

Figure 8 is a plan view of a modified latch bolt construction.

The drawing is merely illustrative of my novel invention and is not definite thereof except as herein claimed.

The reference characters identify the parts shown and described.

2

The latch or lock 1 is secured in an aperture 2 of a closure 3. The closure 3 may be a hinged door (not shown) or it may be any closure or movable means that has relative movement transversely of the latch bolt 9. The latch comprises a housing 4 having a transverse member 5 and a closed end 6. The housing 4 is provided with guides 7 and 8 projecting away from the member 5 in alignment with the remainder of the housing 4.

A slideable latch bolt 9 having a head 10 provided with a cam face 11 projects laterally from the housing 4 defining a space or portion to receive a compression spring 12 between the head 10 and the housing 4 to urge said bolt 9 outwardly of the housing. The bolt 9 is provided with a stop pin 13 and a rack 14 within the housing. The member 5 is provided with a guide way 15 receiving a portion of the rack 14 to guide the same and also to maintain the rack in meshing operation with the pinion 16.

The pinion 16 is provided with trunnions 17 and 18 received in bearings of the housing 4.

The transverse member 5 is provided with guideways 19 and 20 rectangular in cross section substantially midway thereof to guide other racks 21 and 22 which mesh with the pinion 16. The member 5 is also provided with additional guides defining rectangular guide channels 23 and 24 in alignment with the apertured guideways 19 and 20. The guide channels 23 and 24 assist in guiding the racks 21 and 22 and also maintain the racks 21 and 22 in proper mesh with the pinion 16.

The rectangular apertures 19 and 20 also constitute guide means for the stems 24' and 25. One end of each stem 24' and 25 is secured to the central portion of a yoke bar 26 and 27 respectively. Compression springs 28 and 29 surround the stems and are located between the transverse member 5 and the yoke bars 26 and 27. These springs return the manually operated means to normal position. The yoke bars 26 and 27 are provided with end portions 30, 31, 32 and 33 partly located in guideways 7 and 8 of the housing 4. Each pair of end portions supports a finger bar or physical contact piece 34 and 35 respectively. Each contact piece is secured to its supporting end portions by lag bolts 50 36.

In order to lock the bolt 9 against retraction a locking or blocking means 37 is movable into a path of or below one of the racks as 21. This operation prevents the operation of the pinion 16 and in turn prevents the operation of the bolt 9.

The embodiment illustrated consists of a sliding block 37 guided in along the end wall or closed end 6 and further guided by the rectangular block or cleat 38. One wall of the housing 4 and one finishing plate 40 is slotted as at 37' to receive an operating button 39 detachably secured to the sliding block 37.

The finishing plates 40 and 41 are provided with finger recesses 42 and 43 to receive the user's finger tips to operate one of the finger bars.

In order to assemble the finish plates 40 and 41 the bars 34 and 35 should be removed so that the recessed edges (not shown) of the plates 40 and 41 will take over the end portions 30, 31, 32 and 33 of the yoke. When the plates are in place they are secured to the latch or lock housing by lag bolts 44 and 45 and, at least, the corners of the finishing plates are secured to the closure by suitable fastening means such as screws, bolts, rivets, etc., as indicated at 46 of Figure 2. When the finishing plates are in place the finger bars may be replaced and fastened.

It will be seen that the operating means for the lock or latch are always located within the external contour of the same. It is deemed to be of great importance that there are no projections extending outwardly from the faces of the lock.

It is noted that the operating button 39 could be set in a recess (not shown) and it would be of value especially in packaging and transportation.

If my latch construction is used on a closure having a normal approach from one side only, then only one operating pusher will be needed, furthermore, the locking or blocking feature will not be needed, and likewise only one recessed finishing plate will be needed.

In order to make the bolt 9 reversible it should be provided with rack teeth on opposite sides (not shown).

The bolt head 10 is guided in a rectangular tube 46 having an apertured flange or flanges 47 whereby it may be secured or fastened to a closure 2 as clearly shown in Figure 4. In order to remove the stop pin from the bolt 9 the housing 4 may be provided with apertures (not shown) in alignment with the stop pin 13.

The modified construction disclosed in Figure 8 contemplates the use of a spring like spring 12 of Figures 1 and 4. This latch bolt 9' having the rack bar 14' is provided with a bolt head having two beveled or cam faces 11' and 12' instead of one cam face as shown in Figures 1 and 2.

This spring actuated bolt 9' is for use on a swinging door in which the door swings freely in both directions through the door frame. This bolt is used in combination with a two-way keeper (not shown). When the door provided with this latch is closed the two-way latch bolt 9' yieldably retains the door in closed position by cooperating with the two-way keeper.

The rack bar 14' is provided with a transverse aperture 13' to receive a stop pin (not shown).

Having fully shown and described my invention, what I claim is:

1. A latch construction for closures, comprising a housing, said housing being substantially

rectangular in section both longitudinally and transversely, said housing having a closed end portion and an opposite open end portion and a transverse member parallel with the closed end portion, located intermediate said end portions, a slideable latch bolt mounted in said housing, said transverse member having a longitudinal guideway slidably receiving a portion of said bolt, a rotary pinion journaled in said housing between said transverse member and said closed end portion, said bolt having a rack portion in mesh with said pinion, said bolt having a head located outside of said housing and in spaced relation therefrom, a compression spring on said bolt and located between said head and said housing, said housing having guide ways extending from said transverse member to the open end portion thereof, said transverse member having apertures constituting guideways rectangular in cross section, rack bars located respectively in said apertures for reciprocation therein, said rack bars being in mesh with said pinion, yokes having stems, said stems extending respectively into said apertures and adapted to engage the ends of the rack bars to operate the same, the ends of said yokes being slidably fitted in the guideways of the housing, compression springs on the stems and located respectively between the transverse member and the yokes, said transverse member having channel guides in alignment with the apertures, said guides engaging respectively said rack bars, finishing plates having recesses to receive portions of said yokes.

2. A latch construction for closures comprising a housing having a structure therein extending transversely thereof and intermediate the ends of the same, a slideable latch bolt mounted in the housing, said transversely extending structure having a portion for guiding said latch bolt thereover, a rotary pinion journaled in the housing, said bolt having a rack portion in mesh with said pinion and a head located exteriorly of the housing, a spring extending between the housing and the bolt adapted to urge the bolt into a door jamb, rack bars extending through the transversely extending structure for movement axially of the housing and guided by the transversely extending structure, said rack bars meshing with said pinion, operating devices guided by the housing for movement longitudinally thereof and adapted to engage the rack bars to operate the same, said operating devices extending out of the housing and respectively accessible from opposite sides thereof.

GAYLORD A. BRINSON.
